United States Patent Office.

GEORGE L. SMITH AND DANIEL W. KISSAM, OF BRIDGEPORT, CONNECTICUT.

Design No. 4,051, dated May 17, 1870.

DESIGN FOR A LAMP-SHADE.

The Schedule referred to in these Letters Patent and making part of the same

To whom it may concern:

Be it known that we, GEORGE L. SMITH and DANIEL W. KISSAM, both of Bridgeport, county of Fairfield and State of Connecticut, have invented and produced a new and original Design for Lamp-Shades, of which the following is a specification.

The nature of our invention is fully shown in accompanying drawing, which represents a lamp-shade struck up or otherwise formed from sheet metal, so as to be seamless, or without divisions.

The shade is frusto-conical in form, and is corrugated radially from *a* to *b*, having a central opening, *c*, for the passage of the chimney.

That portion of the shade immediately surrounding

this opening is composed of a plane, conical, or dished surface, which is scalloped or indented so as to form a series of converging springs, *d*, which is intended to clasp the chimney.

What we claim, and desire to secure by Letters Patent, is—

The design for a lamp-shade, as shown and described.

GEORGE L. SMITH.
DANIEL W. KISSAM.
